UNITED STATES PATENT OFFICE.

HENRY UNTERMEYER, OF NEW YORK, N. Y.

DESIGN FOR JEWELRY.

SPECIFICATION forming part of Design No. 13,874, dated April 24, 1883.

Application filed December 21, 1882. Term of patent 3½ years.

To all whom it may concern:

Be it known that I, HENRY UNTERMEYER, a citizen of the United States, residing at New York, in the county and State of New York, 5 have invented a Design for Articles of Jewelry, of which the following is a specification.

The invention relates to an improved design for articles of jewelry; and it consists, first, of a peacock upon an oval field of line-work, with 10 ornamental plants in the foreground; and, second, of a peacock upon a countersunk field of line-work, with ornamental plants in the foreground, and inclosed by a flat or lapped border, as shown in the accompanying illustration. 15 The line-work on the oval field is what is known as "straight-line" engine-turning, and the peacock is shown in relief or raised work.

The invention will be fully understood without a more particular description.

It will be understood that the second part of my invention is not limited to the oval frame, nor to any particular form of frame; for instance, a frame which might be oval at top and rectangular at the bottom would be an 25 appropriate border for the peacock and plants upon a countersunk ground of line-work. In practicing the second part of the invention, therefore, I shall adopt any form of border which may seem to me to be appropriate. 30

What I claim as my invention, and desire to secure by Letters Patent, is—

1. A design for jewelry, consisting of a peacock upon an oval field of line-work, with ornamental plants in the foreground, substantially as described. 35

2. A design for jewelry, consisting of a peacock upon a countersunk field of line-work, with ornamental plants in the foreground, and inclosed by a flat or lapped border, substantially as described. 40

Witness my hand this 13th day of December, A. D. 1882.

HENRY UNTERMEYER.

CHAS. C. GILL.
